DIRECTIONAL RELAY CONTROL CIRCUITS
FOR RAILWAY SIGNALING SYSTEMSCrawford E. Staples, Turtle Creek, Pa., assignor
to Westinghouse Air Brake Company, a corpora-
tion of Pennsylvania

Application March 10, 1950, Serial No. 148,967

2 Claims. (Cl. 246—33)

1

My invention relates to directional stick relay control circuits used in railway signaling systems governing the movement of traffic in stretches of single track in which traffic moves in two directions. More particularly, my invention relates to improved directional stick relay control circuits for use in absolute permissive block signaling system employing cascade connected reversible coded track circuits, arranged so that the traffic direction is set up and the headblock signals are cleared by a control, which may be effected either manually or by a train entering an approach section, while the intermediate signals which are controlled solely by the track circuits, are cleared automatically in one direction or the other in accordance with the established traffic direction.

Signaling systems of the absolute permissive block type provide for the control of traffic moving in either direction in a single track stretch by means of headblock signals which display absolute or "stop-and-stay" indications and intermediate signals which display permissive or "stop-then-proceed" indications. The headblock signals control the movement of traffic from passing sidings into the single track stretch, while the intermediate signals control the movement of traffic that has passed a headblock signal and has entered the single track stretch. Each intermediate signal is controlled by an associated track relay and is provided with a directional stick relay normally arranged to become energized when its track relay releases in response to a train passing the associated signal at clear or approach. Each stick relay when energized prepares a circuit for energizing the next signal in the rear, governing traffic movements in the same direction, so as to allow that signal to indicate approach as soon as the portion of the stretch in advance of the signal is vacated by a train and thus permits following movements in the stretch.

The directional stick relays have been controlled in the past jointly by the track relays and by controls transmitted over line wires, but improved systems have been devised for effecting the control of the stick relays solely through the medium of the track rails so as to dispense with the necessity for control line wires. Systems of the latter type are shown in Letters Patent of the United States, Reissue No. 22,915, dated September 16, 1947, (original Patent No. 2,344,573, issued March 21, 1944) and Reissue No. 22,780 dated August 13, 1946 (original Patent No. 2,344,333, issued March 14, 1944) granted respectively on ap-

2

plications filed by James J. Van Horn. The system of Van Horn Reissue Patent No. 22,915 makes use of normally deenergized reversible coded track circuits arranged so that after a traffic direction has been established by energizing the track circuits controlling the signals for the selected direction, the stick relays at the intermediate location are controlled by means of approach relays connected in the track circuits to respond to the approach of a train in the section in the rear of each signal. The system of Van Horn Reissue Patent No. 22,780 is in general similar to that of Reissue No. 22,915, except that the former makes use of normally steadily energized reversible coded track circuits, that is, the track circuits are normally supplied with non-coded energy.

An object of my present invention is to provide novel and improved means for controlling directional stick relays in non-line wire absolute permissive block signaling systems, that is, absolute permissive block signaling systems in which all controls for intermediate signals and directional stick relays are transmitted through the track rails and in which no line wires are used. My improved stick relay control may be used in non-line wire signaling systems in which track circuits are normally energized or normally de-energized, or are of the coded type normally supplied with non-coded energy. A more specific object of my invention is to provide novel and improved means for controlling these directional stick relays by the associated track circuit, so that each directional stick relay becomes energized when its associated track relay releases due to a train entering a corresponding track section in the established direction, but not when an opposing train overruns a headblock signal nor when the track circuit is deenergized in preparation for reversing the direction of traffic.

A further object of my invention is to provide improved means of the type described which is arranged so that the equipment of each intermediate signal location in the stretch is substantially self-contained and does not depend for its operation on special energy impulses transmitted over the track rails from an adjacent signal location.

Another object of my invention is to provide improved means of the type described which is arranged so that the operation of the equipment is independent of changes of operating conditions, such as changes in ballast resistance or in the voltage in the batteries from which energy is supplied to the track circuits.

In practicing my invention I provide, at each intermediate signal location, means for each signal operative upon shunting of its associated track relay, to effect a momentary connection of a source of current and an auxiliary relay in series across the track rails of the section governed by that signal. The auxiliary relay is normally released and is arranged to become picked up only in response to current of the relatively large value caused to be drawn from the source when a train shunt is applied across the rails of the section at or near the signal location.

Thus the auxiliary relay will pick up due to the shunting of its associated track relay by a train entering the section in the established traffic direction, but will not pick up upon operation of the track relay for any other cause, as for example, if the track relay is deenergized preparatory to reversing traffic direction in the stretch.

The intermediate signals may be approach lighted, in which event each such signal will be provided with an approach relay for governing the lighting of the lamp or lamps on the associated signal, with the approach relay for each signal arranged to be connected in series with a source of current across the rails of the section in the rear of the signal and proportioned to pick up only when a train approaches in that section toward the associated signal. The same source may be used at a double intermediate location for controlling the approach relay for one of the two signals at that location and the directional stick relay for the other of the two signals.

The specified objects of my invention, as well as other objects not specifically described above, are obtained by apparatus subsequently to be described and shown in the accompanying drawings.

The system shown and described in this application is closely related to that shown and described in a copending application for Letters Patent of the United States, Serial No. 762,617, filed on July 22, 1947, by Arthur L. Jerome, for a Coded Track Circuit Railway Signaling System, which application is assigned to the same assignee as the present application, and this application contains claims to certain features which are shown but not claimed in the said Jerome application.

I shall describe one form of railway signaling system embodying my invention and shall then point out the novel features thereof in claims.

Referring to the accompanying drawings, Figs. 1A, 1B and 1C, placed side by side in the order listed with Fig. 1A at the left, and Fig. 1D placed beneath Fig. 1B, are diagrammatic views illustrating the track plan and wayside circuits and apparatus for a railway signaling system which embodies my invention. In this application only the portions of the wayside apparatus essential for the understanding of this invention have been shown and the remainder of the equipment may be arranged in any of several arrangements well known in the railway signaling art.

Similar reference characters refer to similar parts in each of the several views.

Referring to the drawings, I have here shown a stretch of single track railroad extending between the ends of two passing sidings, and over which traffic may move in either direction. Movements of trains in and out of the sidings are directed by the track switches 1W and 3W, located at the ends of sidings X and O, respectively. The movement of trains into the single track stretch is governed by wayside entering headblock signals located at the ends of the passing sidings, such

as signals 2RA and 2RB shown in Fig. 1A at the end of passing siding X, and the signals 4LA and 4LB shown in Fig. 1C at the end of passing siding O. Movement of trains leaving the single track stretch is governed by wayside leaving signals such as signals 2LA and 2LB at siding X and signals 4RA and 4RB at siding O. Located at an intermediate point in the single track stretch is a pair of intermediate signals 6L and 6R, which govern traffic moving through the single track stretch. It will be seen, therefore, that each track switch and each wayside signal is designated by a number identifying its location, the signal designations also including the suffix L or R to indicate the direction of traffic movements which the signal governs, that is, to the left or to the right, respectively.

Associated with the switches and signals are a plurality of relays which will be described in detail hereinafter. Each of these relays is identified by a characteristic letter or combination of letters, prefixed by the designation of the switch or signal with which it is associated.

Signals 2RA, 2RB, 6L, 6R, 4LA and 4LB are of the well known color light type, having a green lamp G, a yellow lamp Y, and a red lamp R, which lamps when lit, indicate "clear," "approach," and "stop," respectively. The detailed circuits for signals 2LA, 2LB, 4RA, and 4RB are not shown, since they are not necessary for an understanding of my invention. The entering headblock signals are arranged to be continuously lighted, while the intermediate signals 6L and 6R are arranged to be lighted only when the track section in the rear of the signal is occupied by a train, as will be subsequently described.

The stretch of track between the entering headblock signals 2RA and 2RB and 4LA and 4LB is divided into a plurality of track sections by the usual insulated joints to form track sections 1T, 2R-6LT, 6R-4LT and 3T. The track sections 1T and 3T provide conventional detector track sections at the ends of the passing sidings and each have a conventional direct current track circuit including a track relay such as relay 1TR and a track battery such as 1TB. The remaining track circuits for sections 2R-6LT and 6R-4LT, extending from the ends of the passing siding to the intermediate signals, are of the reversible coded type, which may be connected in cascade when the block includes two or more sections and provide means for controlling the signals for both directions to provide three indications and also for indicating at either end whether or not the single track stretch is occupied, without the use of line wires. The track relays 2RTR, 6LTR, 6RTR and 4LTR, and also the approach relays 6RAR and 6LAR associated with the coded track circuits of sections 2R-6LT and 6R-4LT are code following relays of the biased polar type. These relays are constructed and arranged so that the contacts of the relays are normally biased to their released positions and will pick up when and only when energy flows through the winding in the direction indicated by the arrow thereon. One form of code following relay of this general type is shown, for example, in Letters Patent of the United States No. 2,057,605, issued October 13, 1936, to Herman G. Blosser.

The periodically operating contacts of the code following relays are distinguished from those of the other quick acting relays by dotted lines indicating the alternative position of the contacts, and the contacts of slow acting relays are identified in the conventional manner by the vertical

arrows thereon. It is to be understood that the slow acting relays having condensers bridged across their windings, such for example, as the relay 2RTF shown in Fig. 1A, have release delay periods of about five seconds.

Energy for the operation of the apparatus other than the track circuits is furnished by suitable sources of direct current, such as the batteries shown at each location, the positive and negative terminals of which are designated by the reference characters B and N, respectively.

As previously pointed out, my invention may be employed with various types of absolute permissive block signaling systems including those in which the headblock signals for traffic direction are subject to manual control from a remote office, such systems being commonly known as centralized traffic control systems. The system described herein for purposes of disclosure is of the centralized traffic control type.

Inasmuch as my invention relates only to wayside signaling apparatus, the centralized traffic control system by means of which the direction of energization of the signal circuits and the clearing of the headblock signals is made subject to manual control from the central office is not shown herein, but it is to be understood that this is preferably a remote control system of the code type such as that disclosed in Letters Patent of the United States No. 2,229,249, issued January 21, 1941, to Lloyd V. Lewis, for Remote Control Systems, or in a modified form in a publication entitled "Centralized Traffic Control Systems-Time Code Scheme, Manual No. 506A," published by The Union Switch and Signal Company, Swissvale, Pennsylvania. For an understanding of my invention, it will suffice to point out that the remote control system has at each headblock location a field station which is connected with the control office by a line circuit over which codes are transmitted in either direction for selective communication between the office and the different stations, one at a time. The control codes transmitted to the station serve to operate a group of control relays of the stick polar type, in accordance with the positions of control levers at the office. Two such control relays are shown herein at each station, and these comprise a traffic relay such as relay 2RFS, Fig. 1A, which governs the direction of traffic movements in the single track stretch by cooperation with a similar relay 4LFS at the opposite end of the single track stretch, shown in Fig. 1C, and also, includes two code signal control relays, such as the relays 2RHS or 4LHS, by which the clearing of the correspondingly designated entering headblock signals is made subject to manual control from the office.

Each traffic relay 4LFS or 2RFS when in its normal position as shown, with its contact open, enables the associated end of the single track stretch to become the entering end under proper conditions, that is to say, it enables the adjacent entering headblock signal to be cleared in response to the reversal of the associated code signal control relay 2RHS or 4LHS. Each traffic relay when reversed, so as to close its contact enables the associated end of the stretch to become the exit end. In this position the traffic relay supplies energy to the signal circuits for the block to enable the signals which govern traffic movements toward its location to be cleared.

The present invention relates more particularly to the coded track circuit apparatus, and is an improvement on that disclosed in an applica-

tion for Letters Patent of the United States Serial No. 596,470, filed May 29, 1945, by Henry S. Young for Railway Traffic Controlling Apparatus. In the system of this Young application the coded 5 track circuits are normally deenergized and are set up by manual control by reversing the traffic relay at the exit end of the single track stretch for the desired direction of traffic movement, and then reversing the code signal control relay for the entering signal at the other end of the single track stretch. The system of the Young application is also arranged so that when a train vacates the single track stretch and an indication of that fact has been transferred to the office, 10 the operated traffic relay is restored automatically to normal, and the wayside circuits are thereby restored to their normal deenergized condition. This mode of operation may be employed in connection with the track circuits of my invention, or they may be left energized until the 15 reversal of the traffic direction is required to thereby provide a normally energized system. It is also to be understood that the remote control system preferably includes means for preventing the operation of traffic and signal control relays 20 except when under the proper traffic conditions, so that a signal cannot be put to stop by the operation of any lever other than its control lever, one arrangement suitable for this purpose being 25 disclosed in the above-mentioned Young application.

In the coded track circuit system as disclosed herein, the coded currents are generated by code transmitters of the pendulum type designated 30 180CT and 75CT at the various locations. These code transmitters are energized continuously at the headblock locations and when required at the intermediate locations and operate their contacts periodically at a rate of 180 or 75 times per minute, respectively, to periodically operate a transmitter relay such as relay 2RCT, by which the coded energy of the selected frequency is supplied to the track rails. Each code following track relay, such as relay 2RTR, is provided with 35 a slow release, front contact repeater relay, such as the relay 2RTF, which remains picked up as long as the track relay is responding to coded energy. The code responsive apparatus at the different signal locations is substantially similar 40 and its operation will be understood from the description of that of Fig. 1A, where it will be seen that the closing of front contact *a* of track relay 2RTR in response to the supply of an impulse of coded energy to the winding of relay 2RTR establishes an obvious circuit for supplying energy 45 to the winding of relay 2RTF. Relay 2RTF is rendered slow in releasing its contacts by the condenser connected across the relay winding, so that the contacts of the relay will remain picked 50 up during the intervals in which the control circuit of the relay is opened by the recurrent operation of contact *a* of relay 2RTR. When the contacts of relay 2RTF pick up, its front contact *a* establishes an obvious circuit for supplying energy 55 to a code following repeater relay 2RTP each time that the relay 2RTR releases its contact *a*. Additionally, when relay 2RTF picks up, its contact *b* establishes a circuit for supplying energy 60 to the primary winding of a decoding transformer 2DT over contact *a* of relay 2RTP. As the contacts of relay 2RTP are recurrently picked 65 up and released in response to the code following operation of contact *a* of relay 2RTR, contact *a* of relay 2RTF alternately energizes the lower half 70 and the upper half of the primary winding of 75

decoding transformer 2DT. As a result, current is induced in a secondary winding of the transformer 2DT which current is mechanically rectified by contact *b* of relay 2RTP and supplied to the winding of a slow acting code detecting relay 2RH. It will be seen that the relay 2RH will be energized and picked up when and only when the track relay 2RTR is following code. Transformer 2DT also supplies code frequency energy to a decoding unit 180DU which is of a type well known in the art. The decoding unit 180DU is constructed and arranged so that it will supply energy of a value sufficient to pick up the contacts of "clear" control relay 2RD when and only when the frequency of energy supplied to the decoding unit from transformer 2DT is of the order of 180 cycles per minute. Accordingly, relay 2RD will be energized when and only when the code following relay 2RTR is responding to 180 code. The display of a green or clear aspect by the signals is governed by the "clear" control relay, as will be subsequently described.

The circuits for controlling track switches 1W and 3W which lead to the passing tracks at the ends of the single track stretch have been omitted in order to simplify the drawings, and it will be understood that when switch 1W is locked in its normal position as shown, a normal switch repeating relay 1NWP is energized, and when switch 1W is locked in its reverse position, reverse switch repeating relay 1RWP is energized. The circuits for these relays are completed over the contacts NW and RW of a circuit controller actuated by switch 1W, as will be obvious from an inspection of the drawings. These relays serve to select the signal lighting circuits for signal 2RA or 2RB, in accordance with the position of the switch 1W, the selected signal displaying a yellow aspect when the code detecting relay 2RH is energized alone, or displaying a green aspect when relay 2RD is also energized. The relays 3NWP and 3RWP associated with track switch 3W are similar in their operation and functions to relays 1NWP and 1RWP described above.

The operation of the system is generally similar for both directions of traffic movement and the circuits of Fig. 1C therefore, are similar to those of Fig. 1A, except they are oppositely directed. Likewise, the apparatus at the intermediate signal location of Fig. 1B is similar for each direction but oppositely directed. In Fig. 1B, but one set of decoding apparatus is used, this being arranged for either direction of operation depending upon which of the track relays is operated, and in addition a pair of directional stick relays, such as 6RSR and 6LSR are provided for controlling energization of the track circuit system as required for following train movements in either direction. The directional stick relays are governed at times by an associated relay, such as the relays 6LSAR and 6RSAR, as will be subsequently described.

In describing in detail the operation of the system embodying my invention, it is assumed that the apparatus is in its normally deenergized condition, as shown. It will now be assumed that the operator desires to move a train from right to left through the single track stretch. By operation of the control levers at the control office, the traffic relay 2RFS of Fig. 1A and the signal control relay 4LHS of Fig. 1C are operated to their reverse positions.

At this time, since signal 2LA is at stop, the circuit for supplying energy to the signal repeater relay 2LAPC is interrupted and the con-

tacts of relay 2LAPC are released. The circuit for controlling relay 2LAPC is not shown but it may be of any of several well known types in which the relay is energized when and only when signal 2LA displays a green or yellow aspect. Accordingly, a circuit is established to supply energy of 75 code frequency to the transmitting relay 2RCT. This circuit may be traced from terminal B, over contact *a* of code transmitter 75CT, over back contact *a* of relay 2LAPC, front contact *a* of relay 1TR, over reverse polar contact *a* of relay 2RFS and through the winding of relay 2RCT to terminal N, whereby the contacts of the relay 2RCT are operated at 75 code rate.

When contact *a* of relay 2RCT picks up, it interrupts the connection of track relay 2RTR to the rails of section 2R-6LT, and establishes a circuit for supplying energy from the battery 2RTB through the winding of relay 2RTR and the rails of section 2R-6LT to the winding of relay 6LTR shown in Fig. 1B. This circuit may be traced from the positive terminal of battery 2RTB, over front contact *a* of relay 2RCT, through the winding of relay 2RTR, over rail 5 of section 2R-6LT, over back contact *b* of relay 6LSAR, through the winding of relay 6LTR from left to right, over back contacts *a* and *b* of relay 6LCT in multiple, through rail 6 of section 2R-6LT, and to the negative terminal of battery 2RTB. The direction of flow of energy is such that the contact of relay 2RTR remains released, and the contact of relay 6LTR picks up.

When contact *a* of relay 2RCT releases, the circuit traced above is interrupted, and the contact of relay 6LTR releases. Accordingly, at this time the coded energy supplied to the left hand end of the rails of section 2R-6LT causes the contact of relay 6LTR to be operated at the 75 code rate. The recurrent operation of the contact of relay 6LTR causes energy to be supplied over front contact *a* of the relay to the winding of front contact repeater relay 6LTF, and as a result the contacts of relay 6LTF pick up and remain picked up as long as relay 6LTR is following code.

When contact *a* of relay 6LTF picks up, it establishes a circuit for supplying energy to the code following repeater relay 6TP each time relay 6LTR releases its contact *a*. This circuit may be traced from terminal B, over back contact *a* of relay 6LTF, front contact *a* of relay 6RTF, back contact *a* of relay 6LTF, through the winding of relay 6TP to terminal N. As a result, the relay 6TP will recurrently pick up and release its contacts in accordance with the operation of contact *a* of relay 6LTR. The primary winding of decoding transformer 6DT, and as a result, alternating current is in-circuit including front contact *c* of relay 6LTF and contact *a* of relay 6TP. The recurrent operation of contact *a* of relay 6TP causes energy to be alternately supplied to the upper and lower portions of the primary winding of transformer 6DT, and as a result, alternating current is reduced in the secondary winding of the transformer. This energy induced in the secondary winding is rectified mechanically by contact *b* of relay 6TP, and is supplied to the winding of the code detecting relay 6H to thereby cause the contacts of relay 6H to pick up and remain picked up as long as relay 6TP is following code. Additionally, energy is supplied from decoding transformer 6DT to the decoding unit 180DU, but

since the code rate at this time is only 75 cycles per minute, the energy supplied from the decoding unit 180DU to the relay 6D is insufficient to pick up the contacts of relay 6D.

When relay 6H picks up, its contact *a* establishes a circuit for supplying energy to the operating winding of code transmitter 180CT, and contact *b* of relay 6H establishes a circuit for supplying energy to the transmitting relay 6RCT, which circuit may be traced from terminal B, over front contact *a* of code transmitter 180CT, front contact *b* of relay 6H, over front contact *d* of relay 6LTF, over back contact *a* of relay 6RSR, and through the winding of relay 6RCT to terminal N. As a result, the contacts of relay 6RCT are picked up and released at the 180 code rate.

When the contacts of relay 6RCT pick up, a circuit is established to supply energy from battery 6RTB to relay 4LTR, Fig. 1C. This circuit may be traced from the positive terminal of battery 6RTB, over front contact *b* of relay 6RCT, through the winding of relay 6RHR, over back contact *b* of relay 6RSAR, to the section rail 6 of section 6R-4LT. An additional low resistance path is provided from the positive terminal of battery 6RTB, over front contact *b* of relay 6RCT, over front contact *a* of relay 6RCT, to the rail 6 of section 6R-4LT. The energy flows through rail 6 of section 6R-4LT, through the winding of relay 4LTR, over back contact *a* of relay 4LCT, over rail 5 of section 6R-4LT, over back contact *a* of relay 6RSAR, and through the resistor R2 in multiple with the winding of approach relay 6LAR to the negative terminal of battery 6RTB. The relay 6LAR and resistor R2 associated therewith are selected and adjusted so that the value of energy which flows through the approach relay 6LAR at this time is insufficient to pick up the relay contact. The direction of flow of energy is such that relay 4LTR will pick up its contact and the contact of relay 6RTR will remain released. The shunting of the winding of relay 6RTR by front contact *a* of relay 6RCT affords a lower resistance to the flow of energy in the circuit traced above. When the contacts of relay 6RCT release, the circuit traced above is interrupted and contacts of relay 4LTR release. Accordingly, at this time, the contact of relay 4LTR of Fig. 1C is picked up and released 180 times per minute in response to the coded energy supplied over the rails of section 6R-4LT.

Each time relay 4LTR picks up, energy is supplied over front contact *a* to the winding of front contact repeater relay 4LTF, so that at this time, the contacts of relay 4LTF are picked up, and since relay 4LTF is rendered slow in releasing by the condenser connected across its winding, the relay contacts remain picked up as long as relay 4LTR is following code. Each time contact *a* of relay 4LTR releases, energy is supplied over an obvious circuit including front contact *a* of relay 4LTF to the winding of relay 4LTP. Accordingly, the contacts of relay 4LTP are picked up and released 180 times per minute in accordance with the operation of contact *a* of relay 4LTR.

The primary winding of decoding transformer 4DT is now supplied with energy by an obvious circuit including front contact *b* of relay 4LTF and contact *a* of relay 4LTP. The recurrent operation of contact *a* of relay 4LTP causes energy to be alternately supplied to the upper and lower portions of the primary winding of decoding transformer 4DT, and as a result, an alternating

current is induced in the secondary winding of the transformer having a frequency corresponding to this code rate, which at this time is 180 cycles per minute. This energy is rectified mechanically by the contact *b* of relay 4LTP and supplied to the winding of code detector relay 4LH to thereby cause the contacts of relay 4LH to pick up and remain picked up as long as relay 4LTP is following code. Additionally, energy is supplied from the decoding transformer 4DT to the decoding unit 180DU and since this energy has a frequency of 180 cycles per minute, the decoding unit 180DU supplies sufficient energy to the relay 4LD to pick up its contacts.

Since it is assumed that the code signal control relay 4LHS has been reversed by the central office operator and since switch 3W is assumed to be in its normal position, so that relay 3NWP is picked up, the picking up of relays 4LH and 4LD establishes a circuit for supplying energy to the green lamp of signal 4LA. This circuit may be traced from terminal B, over reverse polar contact *a* of relay 4LHS, over front contact *b* of relay 3TR, over front contact *a* of relay 3NWP, over front contact *a* of relay 4LH, front contact *a* of relay 4LD and through the green lamp G of signal 4LA to terminal N. Accordingly, at this time signal 4LA will display a green aspect, indicating "clear."

If the operator now clears signal 2LA by means of circuits not shown, the relay 2LAPC will become picked up, and its contact *a* transfers the circuit for supplying energy to relay 2RCT from contact *a* of code transmitter 75CT to contact *a* of code transmitter 180CT. As a result, relay 2RCT operates its contacts 180 times per minute and the supply of energy from battery 2RTB to the rails of section 2R-6LT is coded at that rate.

Relay 6LTR, Fig. 1B, will now operate its contacts 180 times per minute in response to the 180 code supplied to its winding, and repeater relay 6TP also operates its contacts 180 times per minute.

Accordingly, energy of a frequency of 180 cycles per minute is supplied from decoding transformer 6DT to the decoding unit 180DU, which now supplies sufficient energy to the relay 6D to cause the relay to pick up its contacts, thereby conditioning the signal 6L to display a green aspect when energy is supplied to its lamp.

The movement of a train from right to left through the single track stretch will now be traced, assuming that the signals 2LA, 6L and 4LA have been conditioned to indicate "clear" as above described.

When the train moves past signal 4LA and enters detector section 3T, detector track relay 3TR is shunted and its contacts release. Contact *b* of relay 3TR interrupts the circuit previously traced for supplying energy to the green lamp G of signal 4LA and establishes an obvious circuit to supply energy to the red lamp R of the signal.

It is to be understood that at this time the code signal control relay 4LHS is restored automatically to normal and an indication of the occupancy of section 3T is transmitted to the control office as described in the manual identified above.

When the train enters section 6R-4LT, the relay 4LTR is shunted and its code following operation ceases. Contact *a* of relay 4LTR releases and remains released at this time, and the supply of energy to relay 4LTF is cut off as a result, but it retains its contacts picked up until the energy stored in the condenser connected across

its winding is dissipated. The contacts of relay 4LTP are picked up continuously for this time interval, but energy is no longer supplied to relays 4LH and 4LD from the transformer 4DT and the contacts of these relays will release, further interrupting the circuit for the green lamp G of signal 4LA.

Subsequently the contacts of relay 4LTF release, interrupting the supply of energy to relay 4LTP and to the primary winding of transformer 4DT.

At this time, relay 6RCT, Fig. 1B, continues to operate its contacts, supplying coded energy from battery 6RTB through the circuit including resistor R2 in multiple with the winding of relay 6LAR. As a result of the shunting effect of the wheels and axles of the train, the current supplied to the rails from battery 6RTB increases as the train approaches signal 6L. The various parts of the equipment are arranged and proportioned so that when the train advances within a substantial distance of the signal 6L, as for example, 4000 feet, the value of current which flows through the winding of approach relay 6LAR becomes sufficient to cause the relay to operate its contact in response to the impulses of energy flowing in the relay winding. Each time contact *a* of relay 6LAR picks up, energy is supplied to the slow release approach repeater relay 6LAP by the circuit which is traced from terminal B, over front contact *a* of relay 6LAR, and through the winding of relay 6LAP to terminal N. Accordingly, relay 6LAP is energized at this time and its front contact *a* establishes the circuit for supplying energy to the green lamp G of signal 6L, which circuit may be traced from terminal B, over front contact *a* of relay 6LAP, front contact *d* of relay 6H, over front contact *a* of relay 6D, and through the green lamp G of the signal to terminal N, thus causing signal 6L to display a green aspect, indicating "clear."

When the train passes signal 6L and enters section 2R-6LT, relay 6LTR is shunted and its contact *a* releases and remains released and cuts off the supply of energy to relay 6LTF. However, the relay 6LTF is slow in releasing and after release of relay 6LTR, the circuit including back contact *a* of relay 6LTR for supplying energy to relay 6TP is established and the contacts of relay 6TP remain picked up for a substantial time interval. The cessation of operation of the contacts of relay 6TP cuts off the supply of energy from the transformer 6DT to relay 6H and 6D and these relays release after a relatively short time interval which is less than the time required for relay 6LTF to release. When contact *d* of relay 6H releases, the supply of energy to the green lamp G of signal 6L is interrupted, and the circuit is established for supplying energy to the red lamp R of the signal.

The relay 6LTF and 6RTF are selected and arranged with condensers of sufficient capacity so that these relays will remain picked up for a comparatively long time interval after the supply of energy thereto has been interrupted by the release of the associated track relay. As previously pointed out, this time interval may be of the order of five seconds, for example.

Accordingly, there will be a substantial time interval between the release of relay 6H and the release of relay 6LT after the supply of energy to each of these relays has been cut off by the cessation of operation of the contact of relay 6LTR. During this time interval, a circuit is established for supplying energy to the winding

of the stick control relay 6LSAR. This circuit may be traced from terminal B, over back contact *a* of relay 6H, over back contact *b* of relay 6LSR, over front contact *b* of relay 6LTF, and through the winding of relay 6LSAR to terminal N. Accordingly, the relay 6LSAR will be picked up during the interval between the time at which relay 6H releases, and the time at which relay 6LTF releases.

When the contacts of relay 6LSAR pick up, energy is supplied from the battery 6LTB through the upper winding of the double wound stick relay 6LSR to the rails of section 2R-6LT, over the circuit which may be traced from the positive terminal of battery 6LTB, through the upper winding of relay 6LSR, over front contact *a* of relay 6RSAR, through rail 6 of section 2R-6LT, through the wheels and the axles of the train occupying the section, through rail 5 of section 2R-6LT, and from thence over front contact *b* of relay 6LSAR to the negative terminal of battery 6LTB. The parts are proportioned and arranged so that with the resistance in the circuit traced above at a comparatively low value, such as will be obtained when the train has just entered the section, the relay 6LSR will be picked up by the value of energy which flows through its upper winding at that time. When relay 6LSR is picked up by the energy flowing through its upper winding, it establishes a stick circuit for itself, which circuit supplies energy to the lower winding of relay 6LSR. This stick circuit may be traced from terminal B, over back contact *a* of relay 6H, over front contact *b* of relay 6LSR, and through the lower winding of relay 6LSR to terminal N.

When relay 6LSR picks up, its back contact *b* interrupts the circuit previously traced for supplying energy to the relay 6LSAR, and relay 6LSAR subsequently releases thereby cutting off the supply of energy to the circuit including the upper winding of relay 6LSR. However, at this time the stick circuit previously traced serves to keep the relay 6LSR energized until relay 6H is again picked up.

A short time later, relay 6LTF releases and its front contact *b* additionally interrupts the circuit for supplying energy to relay 6LSAR, but if relay 6LSR is picked up by this time, the circuit is already interrupted.

At this time the operating winding of code transmitter 75CT, Fig. 1D, is supplied with energy by an obvious circuit including front contact *c* of relay 6LSR.

When contact *b* of relay 6H releases due to the entrance of the train in the section 2R-6LT, the circuit previously traced for supplying energy coded at 180 times per minute to the transmitting relay 6RCT is interrupted. Shortly thereafter, relay 6LSR picks up in the manner described above and its front contact *b* establishes a circuit for supplying energy coded at 75 times per minute to the transmitting relay 6RCT. This circuit may be traced from terminal B at front contact *a* of relay 75CT, over front contact *d* of relay 6LSR, over back contact *a* of relay 6RSR, through the winding of relay 6RCT to terminal N.

As a result, energy is now supplied to the rails of section 6R-4LT at the 75 code rate, and in the event the rear portion of the train still occupies the section 6R-4LT, the approach relay 6LAR will now operate its contact at the 75 code rate, and the relay 6LAP will remain energized. The release time of relay 6LAP is made sufficiently long to bridge the time necessary for the equip-

ment to operate to change the code speed of relay 6RCT from 180 to 75 times per minute.

When the train under discussion vacates the section 6R-4LT, the removal of the shunt decreases the amount of current supplied thereto from the battery 6RTB, and as a result the flow of energy through the winding of relay 6LAR falls below the value necessary to pick up the contact of relay 6LAR and its contact releases and remains released. Accordingly, energy is no longer supplied to relay 6LAP over the circuit including front contact *a* of relay 6LAR, and after a time interval the contacts of relay 6LAP releases.

When contact *a* of relay 6LAP releases, it interrupts the circuits previously traced for supplying energy to the lamps of signal 6L, and as a result, the red lamp R of signal 6L is extinguished.

At the time, as previously explained, energy coded 75 times per minute is supplied to the rails of section 6R-4LT by the operation of the contacts of transmitting relay 6RCT, and when the section is vacated relay 4LTR responds to the 75 code supplied over the rails of section 6R-4LT energizing relays 4LTF and 4LH in a manner similar to that previously described.

However, since the contacts of relay 4LTP are operating at 75 code rate, the relay 4LD does not receive sufficient energy from decoding transformer 4DT and the decoding unit 180DU to pick up its contacts at this time. Consequently, if relay 4LHS is again reversed by the operator, signal 4LA will be cleared in a manner similar to that previously described, except that, since relay 4LD is released the signal will display a yellow aspect, indicating that the next signal is displaying, or is in condition to display, a red aspect.

As the train passes the signal 2LA, and enters detector track section 1T, the detector track relay 1TR is shunted and its contacts release.

When contact *a* of relay 1TR releases, the circuit previously traced for supplying energy to transmitting relay 2RCT is interrupted so that coded energy is not supplied to the rails of section 2R-6LT after the train vacates that section. Additionally, it is to be understood that when the train under consideration enters section 1T, signal 2LA will be put to stop, and as a result, the relay 2LAPC will be deenergized and its contacts will release.

When the train vacates the section 1T, the relay 1TR picks up, and contact *a* of relay 1TR again establishes the circuit for supplying energy to relay 2RCT. However, since the relay 2LAPC is released at this time, the circuit is governed by contact *a* of code transmitter 75CT, so that relay 2RCT supplies energy coded at the 75 code rate from battery 2RTB to the rails of section 2R-6LT.

The relay 6LTR follows the coded energy supplied thereto over the rails of section 2R-6LT, and as a result, the contacts of relays 6LTF and 6H pick up, as previously described. When contact *a* of relay 6H picks up, it interrupts the stick circuit previously traced for relay 6LSR, and relay 6LSR releases its contacts. When relay 6LSR releases its front contact *d*, the circuit previously traced for supplying energy to the relay 6RCT over contact *a* of code transmitter 75CT is interrupted, and additionally, the release of contact *c* of relay 6LSR interrupts the supply of energy to the operation winding of code transmitter 75CT.

The operating winding of code transmitter 180CT is now energized by the circuit including

front contact *a* of relay 6H. Front contact *b* of relay 6H, and front contact *d* of relay 6LTF again establishes the circuit for controlling relay 6RCT over the contact *d* of code transmitter 180CT. Also, the front contact *d* of relay 6H, and back contact *d* of relay 6D prepares the circuit for supplying energy to the yellow lamp of signal 6L should an approaching train cause the relay 6LAP to pick up, as previously described.

With the contacts of relay 6RCT operating at the 180 code rate, energy is supplied from battery 6RTB to the rails of section 6R-4LT at the rate of 180 impulses per minute. Response of relay 4LTR to the coded energy supplied thereto causes the relays 4LTF, 4LH, and 4LD to pick up, as previously explained. Energization of relay 4LD may be employed in any suitable manner to indicate that the entire single track stretch is vacant, but this means is not part of this invention and has been omitted in order to simplify this disclosure.

With the single track stretch unoccupied, and the traffic relay 2RFS reversed to set up the direction of movement from right to left, as described above, it is assumed that the operator at the control office restores the traffic relay 2RFS to normal.

When contact *a* of relay 2RFS opens, the supply of energy to relay 2RCT is cut off. As a result, coded energy is no longer supplied from battery 2RTB over the rails of section 2R-6LT to relay 6LTR, and relay 6LTR releases and remains released.

As previously explained, the release of contact *a* of relay 6LTR results in the release shortly thereafter of the contacts of relay 6H, but the contacts of relay 6LTF remain picked up for a relatively long time interval after release of relay 6LTR.

When contact *a* of relay 6H releases, it establishes the previously traced circuit for supplying energy over back contact *b* of relay 6LSR and front contact *b* of relay 6LTF to the winding of relay 6LSAR. Accordingly, the contacts of relay 6LSAR pick up and connect the battery 6LTB across the rails of section 2R-6LT in series with the upper winding of the stick relay 6LSR.

At this time, since section 2R-6LT is assumed to be unoccupied, the value of energy which flows through the upper winding of relay 6LSR is insufficient to pick up the contacts of the relay. As a result, the relay 6LSR remains released, until the release time of relay 6LTF expires. When relay 6LTF releases, its front contact *b* interrupts the circuit for supplying energy to the winding of relay 6LSAR, so that relay 6LSAR releases and its contacts *a* and *b* disconnect the battery 6LTB and the upper winding of relay 6LSR from the section rails. Accordingly, it will be seen that relay 6LSR is not picked up at this time.

It is apparent that at this time with the section 2R-6LT unoccupied, when the battery 6LTB and the upper winding of relay 6LSR are connected in series across the section rails, energy may flow over the section rails 5 and 6 of section 2R-6LT and through the winding of relay 2RTR. However, it will be noted that the direction of flow of energy through the winding of relay 2RTR is in the direction such that the contacts of this relay will not pick up, so that any possibility of a false operation of relay 2RTR at this time is avoided.

When relay 6H releases its contacts, front contact *a* interrupts the supply of energy to code

transmitter 180CT, and front contact *b* of relay 6H interrupts the circuit for supplying energy to relay 6RCT over contact *a* of code transmitter 180CT, and since relay 6LSR does not pick up at this time to supply energy over its front contact *b* and contact *a* of code transmitter 75CT to the winding of relay 6RCT, the contacts of relay 6RCT remain released.

As a result, coded energy is no longer supplied from battery 6RTB over the rails of section 6R-4LT to the winding of relay 4LTR, and relay 4LTR releases, which results in the release of relays 4LTF, 4LTP, 4LH and 4LD, as previously explained.

The system is now restored to its normal or deenergized condition as shown in the drawings.

From the foregoing, it will be seen that the directional stick relays, such as relay 6LSR is energized when the code operation of the associated track relay ceases as a result of a train entering the corresponding track section at the entrance end thereof, but is not energized if the code operation of the track relay ceases when the section is not occupied.

This result is secured by providing at each intermediate signal location means effective upon release of the code detecting relay governed by a track relay at that location to temporarily connect the associated track battery and an auxiliary relay, in the form of a winding of a multiple-winding stick relay, in series across the rails of the track section in advance of a signal. The auxiliary relay is adjusted so that energy sufficient to pick up the relay contact is supplied from the track battery to the relay winding only if a train is present at that end of the track section, and the relay is additionally governed by the code detecting relay so that the relay if picked up will remain picked up as long as the section is occupied.

When the track battery is connected across the track rails at the end of a track section in series with the winding of the stick or auxiliary relay, the energy supplied to the winding of the stick relay is of a high value if a train occupies that end of the section but is of a low value if the track section is not occupied, or if a train is present in a distant portion of a track section so that a considerable length of track rail is included in the circuit of the track battery and approach relay.

Occupancy of the battery or feed end portion of a track section produces a much greater increase in the value of the energy supplied from the track battery through the winding of the stick relay than is produced by the variations in other conditions, such as changes in ballast resistance or in the voltage of the track battery. Accordingly, at the time the code detecting relay releases the stick relay may be adjusted to respond only to energy of relatively high value so that if that end of the track section is not occupied, the stick relay will not respond to energy of the value supplied as a result of high battery voltage or low ballast resistance, or as a result of both conditions, but so that the stick relay will be certain to respond if that end of the track section is occupied.

As a result, this method of controlling the directional stick relay insures that the relay will be picked up to cause coded energy to be supplied to the track stretch behind the train when release of a code detecting relay is caused by occupancy of a track section, and at the same time it insures that variation in operating conditions will not cause the directional stick relay to be improperly

picked up when release of a code detecting relay occurs because the supply of coded energy over the rails of a track section is cut off for the purpose of deenergizing the track circuit apparatus.

5 My invention is advantageous in that no control pulse need be transmitted from the locations of each end of the single track block to the intermediate signal location, or from one intermediate signal location to another, to cause the system to assume its deenergized condition as is required in some systems. If the supply of coded energy from battery 2RTB, for example, is interrupted during the time when the system is set up for traffic moving from right to left, if no train is occupying the section 2R-6LT the equipment at the intermediate signal location 6L-6R will assume its deenergized condition, as previously explained and will cut off the supply of coded energy to section 6R-4LT, to thereby cause the release of the relays 4LH and 4LD at the other end of the single track stretch.

An additional advantage which is gained from this arrangement is that it causes all the opposing signals governing traffic in the single track stretch to assume the stop position in case a train overruns the entering headblock signal at the exit end of the stretch. If a train moving from left to right should pass signal 2RA at a time when signals 6L and 4LA are cleared for a train moving from right to left, the entrance of the overrunning train into detector section 1T will cause relay 1TR to release with the result that its front contact *a* interrupts the circuit for relay 2RCT. Accordingly, the supply of coded energy to section 2R-6LT is cut off, and as previously explained, the equipment of signal 6L and also of signal 4LA is restored to its deenergized condition with the result that the signals indicate stop.

The equipment operates in a manner similar to that described in the foregoing when the single track stretch is conditioned for traffic movements from left to right, when a train moves through the stretch from left to right, and when the system is being deenergized after such a move, and a detailed description of the operation of the equipment is deemed unnecessary.

It is to be understood that although only one set of intermediate signals, 6L and 6R, is shown in the drawings, the invention is not limited to this arrangement and any number of intermediate signals may be provided if necessary. Additionally, the conventional cut sections and hand operated track switches equipped with electric locks may be interposed as desired without affecting the operation of the arrangement of the equipment embodying my invention.

Although I have herein shown and described only one form of directional relay control circuits for railway signaling systems embodying my invention, it is to be understood that various changes and modifications may be made therein within the scope of the appended claims without departing from the spirit and scope of my invention.

65 Having thus described my invention, what I claim is:

1. In a coded track circuit signaling system, in combination, a stretch of railway track comprising adjoining first and second track sections, first code transmitting means for at times supplying coded energy of a first polarity to the rails of said first section at the end thereof remote from said second section, a first code following track relay connected across the rails of said first track section at the end thereof nearest said

second section and responsive only to energy of said first polarity supplied thereto, second code transmitting means for at times supplying energy of a second polarity to the rails of said first section at the end thereof adjacent said second section, a second code following track relay connected across the rails of said first section at the end thereof remote from said second section and responsive only to energy of said second polarity supplied thereto, a slow release relay energized as a result of operation of said first code following track relay, means operative upon release of said slow release relay for momentarily disconnecting said first track relay from the rails of said first section and for connecting in series across the rails of said first track section at the end thereof nearest said second track section a battery and a first winding of an auxiliary relay, the polarity of said battery being such that said battery is ineffective to cause operation of said second code following track relay, said auxiliary relay having normally released contacts which become picked up when and only when there is supplied through said first winding energy of the value which is supplied when the portion of said first track section nearest said second track section is occupied by a train, a second winding of said auxiliary relay, a stick circuit for supplying energy to said second winding when the contacts of said slow release relay are released and the contacts of said auxiliary relay are picked up, means for supplying coded energy to the rails of said second section while said slow release relay is picked up, and means responsive to the picking up of the contacts of said auxiliary relay for supplying coded energy to the rails of said second section while said slow release relay is released.

2. In a coded track circuit signaling system, in combination, a stretch of railway track comprising adjoining first and second track sections, first code transmitting means for at times supplying coded energy of a first polarity to the rails of said first section at the end thereof remote from said second section; a first code following track relay responsive to energy of said first polarity, a code transmitting relay, a track battery, an approach relay, a directional stick relay having a first and a second winding, and a directional stick control relay, all located at the end of the first section adjacent said second section; means including said code transmitting relay for at times connecting said first code following track relay across the rails of said first section and for at other times recurrently connecting said track battery and said approach relay in series across the rails of said section to ener-

gize the rails of said section with energy of a second polarity, approach controlled means governed by said approach relay, a second code following track relay located at the end of said first section remote from said second section and responsive to energy of said second polarity, a first and a second slow release relay energized in response to the operation of said first code following track relay, said second slow release relay remaining picked up for a time interval subsequent to the release of said first slow release relay on cessation of operation of said first code following track relay, first circuit means for picking up said directional stick control relay during the interval in which said first slow release relay is released and said second slow release relay is picked up, second circuit means effective when said directional stick control relay is picked up for connecting said track battery and the first winding of said directional stick relay in series across the rails of said first section independently of the connections of said approach relay, said first code following track relay, and said code transmitter relay, to thereby momentarily energize the rails of said first section, said second circuit means being arranged so that the momentary energization is of said first polarity and ineffective to operate said second code following track relay, said directional stick relay having normally released contacts which become picked up when and only when there is supplied through said first winding energy of the value which is supplied when the portion of said first track section nearest said second track section is occupied by a train, a stick circuit for supplying energy to said second winding when the contacts of said first slow release relay are released and the contacts of said directional stick relay are picked up, means for supplying coded energy of a first distinctive type to the rails of said second section while said first slow release relay is picked up, and means effective upon picking up of the contacts of said directional stick relay for supplying coded energy of a second distinctive type to the rails of said second section as long as said first slow release relay is released.
